UNITED STATES PATENT OFFICE.

GEORGE LEWIS CLARK, OF MOUNT GILEAD, OHIO.

FEED-RECEPTACLE.

1,000,667.

Specification of Letters Patent. Patented Aug. 15, 1911.

Application filed May 18, 1910. Serial No. 562,064.

To all whom it may concern:

Be it known that J. GEORGE L. CLARK, a citizen of the United States, residing at Mount Gilead, in the county of Morrow and State of Ohio, have invented certain new and useful Improvements in Feed-Receptacles, of which the following is a specification.

My invention relates to the improvement 10 of feed receptacles of that class which are particularly adapted for use in feeding poultry, but which may be adapted for use in supplying feed for live stock of any kind.

The objects of my invention are to provide 15 a simple, inexpensive and effective feed receptacle and dispensing device in which a suspended feed cup will have food automatically discharged therein as the previously discharged food is removed from said 20 cup; to provide improved means for suspending the feed cup in connection with the reservoir or hopper whereby clogging of the hopper reservoir outlet, will be prevented and whereby the feed cup may be adjusted 25 to the desired height with reference to the discharge end of the reservoir or hopper; to provide improved means for supporting my improved device either from the ground or in connection with a building wall or other 30 structure and to produce other improvements the details of construction of which will be more fully pointed out hereinafter. These objects I accomplish in the manner 35 illustrated in the accompanying drawing, in which—

Figure 1 is a side elevation of my improved feed device, Fig. 2 is a central vertical section of the same, Fig. 3 is a plan view with the cover removed, and, Fig. 4 40 is a detail view showing a slight modification of the means for suspending the feed cup rod.

Similar numerals refer to similar parts throughout the several views.

In carrying out my invention, I employ 45 a hollow tapering body 1 having the form of an inverted cone frustum, which body may be formed of sheet metal or other suitable material. The substantially conical body thus produced is adapted to be supported with its lower and smaller end above the ground by means of suitable supporting rods or legs 2, which at desired intervals have their upper ends connected with the outer side of the conical body 1, from which

points said supporting rods or legs incline outwardly and may bear upon a floor or have their lower ends inserted in the ground.

In order to admit of the receptacle being supported from a convenient wall or other upright structure, I have provided the upper end portion of the body 1 with an upturned ear or lug 3 having a hole 4 therethrough to engage a nail or pin which may project from the wall. In order to steady 65 the receptacle and insure its retention in an upright position when suspended by means of the arm 3, I provide at a lower point on said receptacle an outwardly projecting bracket 5 which is adapted to bear against 70 the supporting wall.

Within the upper portion of the receptacle, I provide a fixed, diametrically arranged bar or rod 6 having a central hole 6^a therethrough, of sufficiently large diameter to 75 permit the upper threaded portion of the depending rod 7 to pass loosely therethrough, thus enabling said rod to have a limited swinging movement relative to the receptacle. The lower end of this rod 7 80 which extends centrally through the lower end opening of the receptacle 1, engages and supports the central portion of a feed cup 8, the latter being preferably of greater diameter than the lower portion of the receptacle 1.

Upon the upper threaded end portion of the rod 7 above the bar 6 is provided a suitable form of nut 9 by turning which the rod 7 may be drawn upward or moved downward to increase or decrease the distance between the lower end of the receptacle 1 and the bottom of the cup 8. It will be understood, however, that the lower and smaller end of the receptacle 1 normally projects slightly within the upper open end of said cup.

Upon the upper side of the receptacle 1, I provide a suitable detachable cover 10 which may be of any desired outline and which serves to close the otherwise open upper end of the receptacle.

In utilizing my device, it will be understood that the receptacle 1 is filled to the desired extent with chicken or other feed to be discharged from the lower end thereof and that the feed thus discharged will tend to fill or partially fill the feed cup. As the feed is removed from the cup by the chickens, it is obvious that a substantially equal 110.

amount of feed will be discharged through the lower end of the receptacle into the cup and the cup thus retained in its properly filled condition until all or substantially all 5 of the feed in the receptacle, has been discharged therefrom.

By forming the central opening of the bar 6 of slightly greater diameter than the rod 7, it is obvious that the cup 8 and rod 7 10 may be subjected to a limited swinging movement, which may be caused by the action of the chickens or other animals feeding from the cup. This swinging movement of the rod 7 must necessarily operate to 15 sufficiently agitate the material within the receptacle, as to prevent any tendency of such material clogging in the lower portion of the receptacle, thus insuring a free discharge of feed therefrom.

20 In Fig. 4 of the drawing, I have shown a slightly modified construction of the manner of connecting the supporting rod 7' and bar or rod 6', such means consisting in the formation of a crank bend in the center of the 25 rod 6' and loosely hooking in connection therewith the upper end of the rod 7'. This latter construction may be employed where it is desired to secure a more free swinging movement of the feed cup and its supporting 30 rod or where it is not particularly desirable to adjust the swinging rod as to height.

From the construction which I have shown and described, it will be seen that a comparatively simple feed device is provided, which 35 when constructed of a suitable size will form

an efficient means for feeding poultry or live stock generally.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claim.

What I claim, is—

In a feed device, the combination with an 50 open-end conical casing, a bar extending across said casing and having an opening therein, of a rod extended through said opening and fitting loosely therein, so that such rod has a limited swinging movement 55 relative to the casing, a feed cup secured at the lower end of said rod, a perforated lug secured to the casing adjacent to the top thereof, and a bracket projecting from the side of the casing adapted to coöperate with 60 the lug to retain the casing in a vertical or upright position when the device is attached to a wall or the like.

In testimony whereof I affix my signature in presence of two witnesses.

GEORGE LEWIS CLARK.
